CLAIM

The ornamental design for the electronic cigarette, as shown and described.

DESCRIPTION

FIG. 1 is a front elevation view of a new ornamental design for an electronic cigarette.

FIG. 2 is a rear elevation view of FIG. 1;

FIG. 3 is a top elevation view of FIG. 1;

FIG. 4 is a bottom elevation view of FIG. 1;

FIG. 5 is a right side elevation view of FIG. 1;

FIG. 6 is a left side elevation view of FIG. 1; and,

FIG. 7 is a perspective view of FIG. 1.

(Continued)

The broken lines illustrate portions of the electronic cigarette. None of the broken lines form part of the claimed design.

1 Claim, 7 Drawing Sheets
